UNITED STATES PATENT OFFICE.

ELMER F. HESS, OF PATON, IOWA.

STOCK WATERER.

Application filed September 27, 1921. Serial No. 503,572.

The object of my invention is to provide a stock waterer of simple, durable and comparatively inexpensive construction.

More particularly, my invention relates to a stock waterer, wherein a small amount of water is kept in position where it may be consumed by the stock, the casing containing the small amount of water being in communication with a large reservoir.

10 Still another object is to provide such a stock waterer in the waterer casing of which a limited amount of water will be permitted to be received at any time.

15 Still another object is to provide a float device for controlling the amount of water within the casing, the float device being so adapted that it may be vertically adjusted for changing the amount of water that is permitted to flow into the casing.

20 Still another object is to provide such a float device that is capable of being shifted or adjusted longitudinally to various positions where the amount of leverage used for sealing one end of the pipe, which permits 25 the water to flow into the casing, will be varied.

Still another object is to provide a float device that is entirely supported and secured to the pipe, which it is designed to 30 seal.

With these and other objects in view, my invention consists in the construction, arrangement and combination of the various parts of my device, whereby the objects contemplated are attained, as hereafter more fully set forth, pointed out in my claim, and illustrated in the accompanying drawings, in which:

Figure 1 is a perspective view of my improved waterer, showing the general arrangement of the reservoir relative to the various pens and waterers.

Figure 2 is a central, sectional view taken through my waterer, and

45 Figure 3 is a perspective view of part of the float device of my waterer.

In the accompanying drawings, I have used the reference numeral 10 to indicate an ordinary farm fence, which is used for forming various fences.

50 My waterer includes a casing 11 having a fixed top 12 thereon, the fixed top 12 being provided with an opening 13, whereby access may be had by the stock into the interior

of the casing. A hinged cover member 14 is provided for the casing 11. The cover member is secured to the casing 11 by means of hinges 15.

55 A hook and eye device 16 is used for locking the hinged cover member in position.

The casing 11 is shown in Figure 1 as placed in the ground, but it will be understood that the water may be equally as well used by placing it upon the ground, as by embedding it in the ground.

60 In order to supply the casing 11 with water, I provide a reservoir 17, which may be spaced any distance from the casing 11. In order to permit water to flow from the reservoir 17 to the casing 11, I provide a 70 pipe 18, which is shown embedded in the ground, and in dotted lines.

65 One end of the pipe 18 is extended into one end of the casing 11, as clearly shown in Figure 2 of the drawings. The end of the pipe 18 is projected inwardly, so as to provide an extension within the casing, the purpose of which will be hereafter more fully set forth.

75 In order to limit the amount of flow of 80 water from the reservoir to the casing 11, I provide a float device, the construction of which I will now describe.

80 My improved float device consists of a yoke member 19 adapted to straddle the 85 extended inner end of the pipe 18 and to be secured thereto by means of a bolt 20. A U-shaped member 21 is secured to the lower end of the yoke member 19 and is pivoted thereto by means of the pivot 22. The U- 90 shaped member 21 has secured to it by means of the rivet 23, an L-shaped lever 24. The L-shaped lever 24 comprises a flat bar and consists of a vertical portion 25 and a horizontal portion 26. The vertical portion 95 25 and the horizontal portion 26 are turned a quarter turn, as at 27.

85 The upper end of the vertical extension 25 of the lever is provided with a disc 28, preferably made of leather or some other suitable valve material. The disc 28 is designed, when in one position to abut or rest against the discharge end of the pipe 18.

100 The disc 28 is secured to the upper end of the vertical portion 25 by means of a rivet 105 29.

105 The portion 26 of the lever 24 is provided with an elongated slot 30. Pivotally se-

cured in the slot and slidably mounted therein is a rod 31, having its upper end screw-threaded, as at 32, and having its lower end connected to the portion 26 of the lever by means of the bolt 33. The bolt 33 is received within the slot 30.

Mounted on the screw-threaded end of the rod 31 are a pair of nuts 34, spaced from each other and adapted to receive a member 35 made of floatable material.

From the construction of the parts just described, it will be seen that the member 35 may be adjusted vertically by adjusting the nuts 34 on the screw-threaded portion 32 of the rod 31.

When the water from the reservoir flows into the casing 11, due to gravity, and the water within the casing 11 reaches a predetermined height, the lever 24 will be caused to swing or move on its pivot 22, bringing the disc 28 in position, where it will engage the end of the pipe 18 for sealing the flow of water from the reservoir.

When it is desired to have the height of water within the casing 11 changed, the position of the floatable member 35 on the rod 31 may be varied.

The shifting of the float element relative to the lever 24 will vary the amount of leverage used for causing the float structure to operate against the end of the pipe 18, thus causing it to more thoroughly engage the pipe 18.

It will be seen that I have provided a device, which is very simple and which will very seldom require any attention.

The hinged door member 14 permits ac-

cess into the interior of the casing for adjusting the position of the float device.

It will also be seen that the entire float device is secured to the projected end of the pipe 18.

When it is desired to remove the entire float device, all that is necessary is to release the bolt 20 so that the yoke members 19 will slip off of the end of the pipe 18. The arrangement, whereby the entire float device may be removed, from the casing is a very desirable feature.

Some changes may be made in the construction and arrangement of the various parts of my device, without departing from the essential features and purposes of my invention, and it is my intention to cover by my claims, any modified forms of structure or use of mechanical equivalents, which may be reasonably included within its scope.

I claim as my invention:

In a device of the class described, a casing, an intake pipe projecting thereinto, a supporting member secured thereto, a float arm, comprising a flat bar having a substantially upright portion pivoted to said supporting member and carrying a valve for cooperation with the end of the pipe, and a substantially horizontal portion provided with a longitudinally elongated slot, a float, a rod adjustably mounted in said float, adjusting nuts on the rod on opposite sides of the float, and a member connected with said rod and adjustably mounted in said slot.

Des Moines, Iowa, September 15, 1921.

ELMER F. HESS.
